UNITED STATES PATENT OFFICE.

BENEDICT E. WILLETT, OF DAYTON, OHIO.

DISPLAY-RACK.

1,247,195.

Specification of Letters Patent. Patented Nov. 20, 1917.

Application filed November 8, 1916. Serial No. 130,114.

To all whom it may concern:

Be it known that I, BENEDICT E. WILLETT, a citizen of the United States, residing at Dayton, in the county of Montgomery and State of Ohio, have invented a new and useful Improvement in Display-Racks, of which the following is a specification.

This invention relates to a new and useful improvement in display racks.

10. In groceries and department stores it is desirable that fruits and vegetables be prominently displayed and at the same time readily and conveniently handled. It is the principal object of my invention to meet this need by providing a display rack which is simple and durable in construction, and convenient in operation. It is collapsible for shipment, and when assembled, will firmly hold baskets for movement around a vertical axis, or will receive for like movement, trays, screened receptacles or other display holders. It may be readily moved from place to place in a store, and will support a great weight when desired.
15. The preferred form of embodiment of my invention is illustrated in the accompanying drawings, of which Figure 1 is a plan view of one of the basket holding frames. Fig. 2 is an elevational view of a plurality of the 20 rotatable basket holders in position upon the movable base. Fig. 3 is an elevational view of one of the vertical bracing members for the basket holding frames. Fig. 4 is a top plan view of the movable bottom or spider. Fig. 5 is a top plan view of one of the 25 partitioned receptacles. Fig. 6 is a plan view of a receptacle, without partitions, that may be substituted in the rack for the partitioned receptacle or a basket holder. Fig. 30 7 is a side view of a receptacle with a screened rim. Fig. 8 is a plan view of the notched disk which receives the removable partitions at the center of the receptacle. And Fig. 9 is an elevational view of the 35 device which holds said partitions at the circular rim of said receptacle.

Throughout the specification and drawings, similar reference characters denote corresponding parts.

40. In a detailed description of the preferred form of embodiment of my invention, the

numeral 1 designates a tubular member that is disposed vertically within a movable base or spider. This member 1 is suitably secured to a circular base plate 2 to which are 45 bolted diagonal members 3 that extend outwardly to the meeting points of side members 4 and end members 5 which are preferably connected to form a square. This frame is supported by casters or rollers 6, one of 50 which is secured below the base plate 2, while the remaining four are positioned beneath the corners of said frame. The tubular member 1 at its top supports an apertured plate 7 to which extends, from each 55 corner of the square base frame, a bracing piece 8. This construction makes a simple, compact and durable base that may be easily taken apart for shipment. When assembled it may be readily moved from place to place, 60 and will efficiently support the display rack now to be described.

The tubular member 1 extends upwardly through pipe flanges 9 and 10 between which are secured the ends of looped pieces 65 11 which form the frames of the basket holders. These looped pieces are constructed of metal, and are preferably egg-shaped in appearance. The inner straight 70 ends 12 of these holders are radially disposed about the flanges 9 and 10, their elliptical portions beginning at points in a common circumference described around the tubular member 1. (See Figs. 1 and 2.)

The adjacent portions 12 of the above described metallic pieces are connected to each other and the flanges 9 and 10 as follows. These portions 12 straddle screw-threaded bolts 13 which pass through the tubular flanges 9 and 10 near the circumferential 75 edges thereof, nuts 14 being applied to the lower ends of said bolts to draw said flanges tightly against the metallic pieces between them. The adjacent inner ends of the pieces 80 11, between the bolts 13 and the tubular portions of the flanges 9 and 10, are connected by means of bolts 15. The inner ends of the pieces 11 are thus firmly, yet removably, secured to the pipe flanges 9 and 10. At 85 the points where they leave the common circumference before referred to, the adjacent parts of the pieces 11 are connected together 90.

by bolts 16, each of which receives a notched portion 17 of a vertical bracing piece 18 for a purpose now to be explained. (See Figs. 1 and 31)

5 In my improved display rack it is very desirable that more than one of the basket holders be used, and in order to accomplish this object the vertical bracing pieces 18 and other elements now to be described, are employed. In order to support a similar basket holder above it, the pipe flange 9 of the upper holder is threaded to receive a tubular coupling member 19 which is threaded into the tubular portion of the pipe flange 10 of 15 the basket holder below. The tubular member 1 extends upwardly through the flanges 9 and 10 of the lower basket holder, into the coupling member 19, whereby the basket holders connected by the latter may be 20 revolved around the tubular member 1, the apertured plate 7 forming a bearing support for the tubular portion of the flange 9 of the lower basket holder.

In order to brace the two basket holders thus connected for rotatable movement about the tubular member 1, the vertical members 18 are placed between the corresponding adjacent portions of the looped pieces 11 so that the bolts 16 will lie in the notches 17 30 of said members, after which the nuts 20 on said bolts are turned to tightly compress said bracing members between the adjoining parts of the looped pieces. A firm and readily removable connecting structure for the 35 basket holders is thus obtained.

While any number of basket holders a merchant desires, may be thus connected for rotatable movement upon the movable base, I have shown four in Fig. 2. Each is secured to the one below by a tubular coupling member 19 and the vertical bracing members 18, in a manner similar to that just described for connecting the two lowermost holders. The basket holders are thus adapted to be readily increased in number, and 45 easily separated from one another and the movable base by releasing the vertical bracing members 18 and unscrewing from their respective pipe flanges, the coupling members 19. In the case of the lowermost basket 50 holder, the coupling member 19 and flanges 9 and 10 must be lifted above the tubular member 1 which projects into them.

The looped pieces of each basket holder 55 may then be separated from each other and the pipe flanges 9 and 10, by removing the bolts 13, 15 and 16, whereby they are in a condition to be conveniently shipped. When the racks are assembled, the looped piece of 60 each holder will support a basket of fruit, vegetables or other merchandise in such a manner that, by rotating the rack or moving the base, it may be brought into a convenient position for displaying its contents to a cus-

tomer or permitting a clerk to easily remove 65 a part or all of them.

In Fig. 5 there is shown a partitioned receptacle to which the pipe flanges 9 and 10 may be secured, whereby it may be substituted for a basket holder in the display rack 70 just described. Connected to the flange 10 is a notched cylinder 22, each notch 23 of which receives a removable partition 24. The outer end of each of said partitions is received between the flanges 25 of a supporting piece 26 secured to the bottom of the receptacle 21 near the circular rim thereof. (See Figs. 5, 7, 8 and 9.) This rim may comprise a screen 27 as shown in Fig. 7. The construction above described makes it 80 possible for partitions to be readily added to, or removed from, the receptacle 21, and any other suitable one for accomplishing this purpose may be employed without departing from the spirit of the invention. 85

In Fig. 6 there is shown a circular tray 28 without partitions, and adapted to be substituted for the partitioned receptacle 21 or the basket holders, in the rack before described. Almst any form of receptacle, 90 tray or holder when equipped with the pipe flanges 9 and 10, may be conveniently made a part of my improved display rack.

I do not wish to be limited to the details of construction and arrangement herein 95 shown and described, and any changes or modifications may be made therein within the scope of the subjoined claims.

Having described my invention, I claim:

1. A display rack comprising a base, a 100 basket carrier rotatably mounted thereon, said carrier comprising a pair of central flanges, looped members radially disposed about said flanges, fastening elements connecting said flanges together, and means disposed between said fastening elements and the vertical axis of said flanges, for removably connecting the inner ends of said looped members. 105

2. A display rack comprising a base, a 110 basket carrier rotatably mounted thereon, said carrier comprising a pair of central flanges, looped members radially disposed about said flanges, bolts connecting said flanges together, the inner adjacent ends of 115 said looped members straddling said bolts, and means disposed between said bolts and the vertical axis of said flanges, for connecting the inner ends of said looped members.

3. A display rack comprising a base, a 120 basket carrier rotatably mounted thereon, said carrier comprising a pair of central flanges, looped members radially disposed about said flanges, fastening elements connecting said flanges together, the inner adjacent ends of said looped members straddling said fastening elements, bolts disposed 125 between said fastening elements and the

vertical axis of said flanges, for connecting the ends of said looped members between the flanges, and means connecting the outer adjacent parts of said looped members at 5 points equidistant from the axis of said flanges.

In testimony whereof I have hereunto set my hand this 6th day of November, 1916.

BENEDICT E. WILLETT.
